UNITED STATES PATENT OFFICE.

THOMAS F. MOORE, OF DOVER, NEW JERSEY.

TRENCHING APPARATUS.

1,378,970.

Specification of Letters Patent. Patented May 24, 1921.

Application filed February 18, 1919. Serial No. 277,797.

To all whom it may concern:

Be it known that I, THOMAS F. MOORE, of Dover, in the county of Morris, in the State of New Jersey, have invented new and useful Improvements in Trenching Apparatus, of which the following, taken in connection with the accompanying drawings, is a full, clear, and exact description.

This invention relates to certain improvements in apparatus for excavating and back filling trenches for sub-surface conduits and similar work, which is necessarily carried on within relatively narrow limits particularly in the thoroughfares of more or less congested districts, and is somewhat similar to that set forth in my patent of June 18, 1918, No. 1,270,240, in that it contemplates the use of a longitudinally swinging digging dipper and a bucket together with suitable hoists mounted upon a car, which in turn is movable along a track between a power house and a suitable anchorage for the dipper operating cable, the bucket being operated by a separate cable from the power house.

The material to be excavated such as loose earth, sand, gravel, clay, shale, and solid rock, often varies at different depths or levels and at different localities in the length of the trench so that it becomes necessary at times to change the method of and implements for excavating.

It has been found, however, that practically all of these materials may be expeditiously and economically handled by means of a power operated digging dipper for use in excavating the looser materials, while the bucket may be used in rock-cuts and other places where it is necessary to reduce the materials by blasting or other means.

The main object, therefore, is to mount the dipper and bucket upon the same car in such a manner that either may be used for excavating and back filling or loading into wagons without interference one with the other.

The specific object as distinguished from my prior patent referred to, is to place the cable supporting sheaves for the dipper and bucket in such relative position upon the car that the cable connection between the dipper, and its cable-supporting sheaves may have a more direct forward draft upon the dipper when the latter is swung down-

wardly and rearwardly beyond a perpendicular or to the limit of its rearward swinging movement, and at the same time to reduce to a minimum the lifting thrust of the dipper on the rear end of the car as the dipper is drawn forward and upward in the operation of digging.

Another object is to place the cable-supporting sheaves for the fall block of the bucket on the rear end of the car so that the corresponding fall-block and its supporting cable may operate freely between the opposite arms of the dipper-supporting beam, all of which enables the car to be made considerably shorter and, therefore, less cumbersome and expensive than that shown in my patent previously mentioned.

A further object is to support the locking member for the fall-block of the dipper in such a manner that it may be automatically shifted from its normal locking position by a portion of the adjacent cable when the dipper is rocked downwardly to its extreme rearward position for the purpose of reducing to a minimum the frictional wear between the cable and locking pin.

A further object is to operate the movable bottom of the dipper by means of toggle-arms and suitable actuating means therefore all of which are mounted directly upon the dipper-supporting beam so that the bottom of the dipper may be opened or closed at will at any point in the arc of movement of said dipper.

Other objects and uses relating to specific parts of the trench apparatus will be brought out in the following description.

In the drawings—

Figure —1— is a side elevation of a trenching apparatus embodying the various features of my invention, the dipper being shown in its digging position at the extreme limit of its rearward movement, portions of the dipper operating cable at the rear of the car being broken away.

Fig. —2— is a longitudinal vertical sectional view through the upper portion of the car and dipper, which latter is shown as locked in its extreme upper position, the bucket being also shown as locked in a corresponding position, thus permitting the car to be drawn forwardly or rearwardly by the power device hereinafter described.

Fig. —3— is an inverted plan of the dipper and adjacent portion of its supporting beam showing more particularly the toggle-arms and operating means therefor, for opening and closing the bottom of the dipper, a portion of said toggle-arms being shown in section.

Fig. —4— is a top plan of a fragmentary portion of the dipper-supporting beam showing the rotary drum and cables controlling the operation of the toggle-arms previously mentioned.

Fig. —5— is a longitudinal sectional view taken on line 5—5, Fig. —4—, showing more particularly the means for locking the toggle controlling drum in its adjusted position.

The means illustrated for carrying out the objects stated comprises a track —A— having its rails running along opposite sides of the line of trench and adapted to support a power house —B—, a car —C—, and an anchorage —D—, the power house and anchorage being located considerably apart lengthwise of the track and are provided with suitable wheels resting upon the rails of said track to permit them to be easily moved thereon, but are preferably held against such movement by suitable blocking (not shown) when the apparatus is in operation.

30 The power house contains the motive power such as steam engine —B'— and cable drums —b— and —b'—.

The anchorage —D— is adapted to receive and support weights —d— sufficient to counteract any load which may be placed upon the dipper operating cable as —1— which is passed around the sheave —d'— on the upper portion of the anchorage —D— as shown more clearly in Fig. —1—.

40 The car —C— is movable along the track —A— between the power house —B— and anchorage —D—, and is similar to that set forth in my Patent 1,270,240, previously mentioned, except that it is somewhat shorter and is specifically adapted to the altered arrangement of the supporting means for the fall-blocks, and other structural differences which may be hereinafter pointed out.

The general structure of the car is that of 50 a trussed bridge composed of opposite upright longitudinally extending sections —2— of sufficient height and transverse spaced relation to permit a wagon or similar vehicle to pass between them from end to end, and 55 also affording ample clearance for the operation of the dipper and bucket in the intervening space for loading the vehicles, or for excavating or back filling as may be desired.

60 The upper portion of these uprights —2— are rigidly connected by upwardly converging braces —3— and a central lengthwise ridge beam —4— suitably secured to and between braces —3— so as to form a unitary 65 frame having a lengthwise passage thereto

from end to end below the ridge beam for the free operation of the dipper and bucket in the intervening space, said frame being also provided at its ends and sides with elevated platforms —5— and —6— along which the attendant may readily pass.

For convenience of description the end of the car nearest the power house will be termed the front end, while that nearest the anchorage will be termed the rear end.

A digging dipper —7— is mounted upon one end of a pair of parallel arms —8— which are spaced apart transversely at opposite sides of the longitudinal center of the car and constitutes what may be termed a supporting beam for the dipper of sufficient length to allow the dipper to enter the ground a considerable distance below the surface thereof for trenching purposes, and is preferably of greater length than the car 80 and is movable longitudinally and also about a transverse axis so that when the dipper is elevated to a position in proximity to the front end of the car the rear end of the beam will extend some distance beyond the corresponding end of the car, as shown in Fig. —2—.

The arms —8— of the dipper-supporting beam are arranged at opposite sides of the ridge beam —4—, and are provided along their lower rear edges with toothed-racks —9— meshing with pinions —10— which are secured to a transverse shaft —11—, the latter being journaled in suitable bearings on the upper end of the braces —3— near the rear end of the ridge beam —4— and constitutes a pivot about which the dipper-supporting beam is adapted to rock.

The arms —8— are also guided in rocking yokes —12— which are mounted on the rock shaft —11— at opposite sides of the rear braces —3— near the ridge beam —4—, and are provided with rollers —13— for engaging the upper edges of said arms —8— at the opposite sides of the shaft —11— for holding the racks —9— in engagement with their pinions —10—, and also for guiding the dipper supporting beam in its longitudinal movement.

In other words the dipper supporting 115 arms —8— are slidable longitudinally in their respective yokes —12—, which in turn are movable with said arms about the axis of the shaft —11—, while the pinions —10— and rollers —13— constitute roller bearings 120 for guiding the dipper-supporting arms in their longitudinal movement with a minimum amount of friction, the pinions —10— and racks —9— serving as a means by which the dipper may be locked in any position of 125 adjustment longitudinally through the medium of a suitable brake mechanism presently described.

This brake mechanism may be of any desired construction consisting in this in- 130

stance of a wheel —14— secured to the shaft —11— and adapted to be engaged by a brake shoe —15— which is mounted on a crank shaft —16— having a crank arm 5 —17— connected by a cable —18— to a hand lever —19— as shown in Figs. —1— and —2—, said lever being provided with the usual pawl for engaging a relatively fixed rack —20— to hold the brake in its 10 operative position.

The ridge beam —4— is usually made of opposite plates in transversely spaced relation for receiving between them separate pairs of sheaves —21— and —22— located 15 respectively near the front and rear ends of the car, the forward sheave being adapted to support the adjacent end of the dipper operating cable —1—, while the other pair of sheaves —22— are adapted to support the adjacent end of a bucket operating cable —1'—.

The forward end of the cable —1— is attached to the drum —b— in the power house —B— and extends rearwardly over 25 the top of the car upon suitable sheaves on the forward and rearward ends thereof, some distance to the rear end of the car where it passes around the sheave —d'— on the anchorage —D— and is returned 30 over suitable sheaves on the top of the car and around one or more sheaves —21—, on the front end of the car and is attached to a fall-block —23— on the upper edge of the dipper —7—, as shown more clearly in 35 Fig. —2—.

The forward end of the other cable —1'— is attached to the drum —b'— in the power house —B— and extends rearwardly over 40 suitable sheaves as —24— on the top of the car and around one or more sheaves —22— on the rear end of the car, and is attached to a fall-block —25— which is adapted to support a bucket —26—.

Both of the fall-blocks are adapted to 45 play between the opposite plates of the ridge beam —4— and therefore in a vertical plane substantially midway between the opposite arms —8— of the dipper-supporting beam, and are also adapted to swing 50 longitudinally between the opposite uprights of the car when released and lowered.

The use of either the bucket or dipper is generally determined by the materials to be excavated, as previously explained, and it 55 therefore becomes necessary to provide some means for locking the fall-block for both of the devices in their extreme upper position so that the one not in use may not interfere with the one in operation, and for 60 this purpose is provided a pair of locking pins —27— and —28— one for each fall-block, each locking pin extending transversely across the intervening space between the side plates of the right beam —4— 65 and through longitudinal elongated inclined

slots —29— and —30— therein, as shown more clearly in Fig. —2—, to allow the pins to be moved into and out of holding engagement with their respective fall blocks —23— and —25—.

Each locking pin may be shifted from its holding position by an inverted U shaped hand lever —31— which is pivoted at —32— to the opposite plates of the ridge beam —4— so as to move longitudinally of the car, its opposite arms —31— being slotted vertically to receive the ends of the locking pin and permit said pin to automatically interlock with its fall-block when the latter is drawn to its extreme upward position 80 and then slightly released.

The dipper is adapted to swing longitudinally of the car through an arc of approximately 90° which, of course, materially changes the angle of its supporting 85 cable relatively to the vertical plane or planes in which the sheaves —21— are located, and in order that the cable may assume its various angles without excessive friction with the locking pin —27—, the 90 slot —29— is elongated rearwardly a sufficient distance to allow the pin —27— to pass beyond a direct line between the front faces of the fall block —23— and sheave —21— when the dipper is at the limit of 95 its downward and rearward swinging movement, said slot being inclined to cause the pin to automatically return to its locking position.

By locating the cable supporting sheaves 100 —21— for the fall-block —23— in close proximity to the forward end of the car, and by pivoting the supporting beam in close proximity to the rear end of the car enables the portion of the cable between the fall-block —23— and sheaves —21— to assume an efficient forward-draft angle when the dipper is swung to its extreme rearward and downward position without excessive lifting thrusts between the dipper and car 110 and enables the car to be made somewhat shorter and therefore more economically than that shown in my patent previously mentioned.

When the dipper is in operation the 115 bucket —26— is preferably removed from its fall-block —25— and allowed to rest on the bottom of the trench or elsewhere, where it is available for use when it becomes necessary to change the mode of excavation from the dipper to the bucket, under which conditions the dipper may be drawn to its extreme upward position by the cable —1—, and locked in place by its pin —27—.

The dipper —7— is preferably of the bottom-dump type and is braced to the beam by opposite triangular plates —33— to which the movable bottom —7'— of the dipper is hinged at —34—, just to the rear of the rear wall of the dipper, as shown in Fig. 130

—2—, thus allowing the bottom to swing by its own weight and the weight of the load to its open position when released.

Suitable means is provided for positively closing the swinging bottom of the dipper and preferably at any position of adjustment of said dipper and its supporting beam, and for this purpose the hinge sections of the bottom —7— are connected at 5 points some distance below the pivot —34— to one of a pair of toggle-arms —35— which are pivoted to each other at —36—, the other arm being pivotally connected at —37— to suitable plates —38— on the arms 10 —8— of the dipper-supporting beam some distance toward the free end of said arms. 15 The flexing joint of the toggle-arms —35— is connected by a link —39— to a sheave block —40—, the sheave of which 20 is engaged by a cable —41— having one end attached to a fixed support —42— on the dipper-supporting beam, and its other end attached to a rotary drum —43— on the same beam, said drum being provided 25 with a hand-crank —44— at one side of the beam for operating the drum to wind the cable thereon, and thereby draw the toggle-arms toward a straight line for the purpose of positively closing the bottom —7— of 30 the dipper.

In order that the drum —43— may be locked against reverse rotation to hold the bottom of the dipper in its closed position it is provided with a ratchet wheel —46— 35 adapted to be engaged by a movable detent —47— shown in Figs. —4— and —5—.

If the dipper is to be operated for excavating or loading and back filling the bucket —26— will, of course, be removed from its 40 fall-block —25— whereupon the operation of the drum —b— in one direction by means of suitable clutch connections with the engine will lift the fall block —23— and dipper a sufficient distance to allow the locking 45 pin —27— to be thrown from its locking position through the medium of the hand lever —31— at which time the drum —b— may be released to allow the dipper to rock downwardly and rearwardly to the desired position 50 to enable its teeth to be brought into engagement with the material that is to be excavated, it being understood that during this initial lowering of the dipper the beam —8— will be held against longitudinal 55 movement by the rack and pinion —9— and —10—, and by the application of the brake —15— will prevent the rotation of the pinion relatively to the rack.

In order that this operation may be more 60 clearly understood it may be stated that the distance between the axis of movement of the dipper-supporting beam and vertical plane of the front supporting sheave —21— for the fall-block —23— may be slightly

less than the distance between the same axis 65 and the bottom of the car, to allow the dipper to swing freely from its normal up position to its extreme rearward position above the surface of the ground to be excavated while the brake is applied, at which time the 70 brake —15— may be released to allow the dipper to descend by its own weight to its digging position in contact with the ground.

The drum —b— may then be operated to draw the dipper forwardly and upwardly 75 for loading or to move the car rearwardly over the back-filling and the dipper may be dumped at any period in such movement by simply releasing the drum —43—.

If the condition of the material is such 80 that it cannot be loosened or removed by the operation of the dipper, and it becomes necessary to loosen it by hand or blasting, said dipper may be hoisted and locked in its extreme upward position, and the fall block 85 for the bucket may be lowered into the trench for raising the loaded buckets therefrom, and causing its fall block to engage the corresponding pin —28—.

When the bucket or dipper is arranged in 90 its extreme upward position, either loaded or unloaded the limitations of movement of the corresponding cable will allow the latter to be operated by its drum —b— or —b'—, along the track, as may be necessary, 95 as the work of excavating progresses or in dumping the loads for back-filling or into other conveyers.

What I claim is:—

1. Trenching apparatus comprising in 100 combination with a track along the trench line, a power device and an anchorage both stationed some distance apart, said anchorage having a sheave thereon, a car movable along the track between said power device 105 and anchorage, a cable-supporting sheave on the front end of the car, a dipper having a supporting beam movable about an axis near the rear end of the car and having an independent endwise movement, a fall block 110 attached to said dipper, and a cable passing around the sheaves and fall-block and attached to the power device.

2. Trenching apparatus comprising in 115 combination with a track along the trench line, a power device and an anchorage both stationed some distance apart along the track, and provided respectively with a rotary drum and a sheave, a car movable along the track between the power device and anchorage and provided with a cable supporting sheave near its front end, a dipper having spaced supporting arms mounted on the rear end of the car to swing lengthwise thereof and having an independent endwise 120 movement, a fall-block attached to the dipper, a cable extending lengthwise of the car 125 between the dipper arms, and having one

end attached to said drum and its other end passed around the anchorage sheave and returned to the car over the second named sheave and attached to the fall-block.

- 5 3. Trenching apparatus comprising a car movable along the trench line, a dipper mounted on the car to swing about an axis at the rear end of the car, a fall-block attached to the dipper, a sheave on the front 10 end of the car, a cable passed around the sheave and attached to the fall-block, and means for winding and unwinding the cable.

4. Trenching apparatus comprising a car movable along the trench line, a dipper 15 mounted on the car to swing about an axis at the rear end thereof, a fall-block attached to the dipper, a sheave on the front end of the car, a cable passing around the sheave and attached to the fall-block, means for 20 winding and unwinding the cable, said dipper having spaced supporting arms, a sheave mounted on the car near the rear end thereof between said axis and the first named sheave, a bucket-supporting fall-block, a 25 cable passed over the second named sheave and between said arms and attached to the last named fall-block, and power operated means for winding and unwinding the second named cable.

- 30 5. Trenching apparatus comprising a frame along the trench line, a dipper having a supporting beam hingedly mounted upon the frame, a fall-block attached to the dipper, a dipper operating cable passed around the fall-block, a bucket-supporting fall-block movable vertically between the axis 35 of movement of the dipper-supporting beam and the first named fall-block, a bucket operating cable supporting the second named 40 fall-block, and sheaves mounted on the frame for supporting said cables.

6. Trenching apparatus comprising a track along the trench line, a car movable along the track, a dipper-supporting beam 45 hingedly mounted upon one end of the car to swing vertically lengthwise thereof, a fall-block attached to the dipper, a dipper-operating cable supporting the fall-block, sheaves on the front end of the car for supporting the cable, a bucket-supporting fall-block, a bucket operating cable supporting the second named fall-block, and supporting sheaves for the second named cable mounted on the car between the axis of movement 50 of the dipper-supporting beam and the first named sheaves.

7. In a trenching apparatus the combination of an elevated frame along the trench line, a dipper having a supporting beam 60 mounted on the frame to swing vertically and longitudinally of said frame and having an independent endwise movement, a sheave on the frame some distance from the axis of movement of the dipper supporting beam,

a fall-block attached to the dipper, a cable 65 attached to the fall-block and passing around said sheave, a second sheave mounted on the frame nearer to the axis of movement of the dipper supporting beam than the first named sheave, a cable supported by 70 the second named sheave, and a bucket-supporting fall-block attached to the second named cable.

8. In a trenching apparatus the combination of an elevated frame along the trench 75 line, a dipper having a supporting beam mounted on the frame to swing vertically and longitudinally of said frame and having an independent endwise movement, a sheave on the frame some distance from 80 the axis of movement of the dipper supporting beam, a fall-block attached to the dipper, a cable attached to the fall-block and passing around said sheave, a second sheave mounted on the frame nearer to the axis of 85 movement of the dipper supporting beam than the first named sheave, a cable supported by the second named sheave, and a bucket-supporting fall-block attached to second named cable, said dipper supporting 90 beam having spaced arms, the second named cable and fall-block attached thereby being movable between said arms.

9. In a trenching apparatus, a track 95 lengthwise of the trench, a car movable along and upon the track, rotary drums at one end of the track, an anchor at the opposite end of the track, a sheave on the anchor, a cable attached to one of the drums and extended across the top of the car and 100 around the sheave on the anchor and returned over the top of the car to a point near the front end thereof, sheaves on the car for supporting the returned end of the cable, a fall-block attached to said cable 105 after passing around the sheaves, a dipper supporting beam mounted on the rear end of the car to swing vertically and lengthwise of said car and having an independent endwise movement, connections between the dipper and fall-block, additional sheaves mounted on the car near the rear end thereof, a separate cable passed around said sheaves, and a bucket supporting fall-block carried by the second named cable, said second 110 named cable being extended forwardly over the top of the car and attached to the other drum.

10. In a trenching apparatus, the combination of a car movable along the line of 115 the trench, a dipper and a supporting beam therefor mounted upon the car to swing vertically and longitudinally thereof about an axis near the rear end of the car, a pair of sheaves mounted on the car near the front 120 end thereof, a fall-block attached to the dipper, a cable passed around said sheaves and supporting the fall-block, an additional 125

set of sheaves mounted on the car some distance to the rear of the first named sheaves, a cable passed around the second named sheaves, and a bucket supporting fall-block 5 carried by the second named cable.

11. In a trenching apparatus, the combination of a car movable along the line of the trench, a dipper and a supporting beam therefor mounted upon the car to swing vertically and longitudinally thereof about an axis near the rear end of the car, a pair of sheaves mounted on the car near the front end thereof, a fall-block attached to the dipper, a cable passed around said sheaves 15 and supporting the fall-block, an additional

set of sheaves mounted on the car some distance to the rear of the first named sheaves, a cable passed around the second named sheaves, a bucket supporting fall-block carried by the second named cable and separate 20 locking pins mounted on the car for locking and releasing said fall-blocks in and from their uppermost positions.

In witness whereof I have hereunto set my hand this 10th day of February, 1919. 25

THOMAS F. MOORE.
